RECEPTACLE FOR PASTE-PERFUMERY

Yasui Kumai, Okegawa, Japan, assignor to
Shiseido Co., Ltd., Tokyo, Japan

Filed Feb. 9, 1973, Ser. No. 331,236

Term of patent 14 years

Int. Cl. D9—03

U.S. Cl. D9—193

Fig. 1

Fig. 2

Fig. 3

Fig. 4

Fig. 5

Fig. 6

Fig. 7

Fig. 8

FIG. 1 is a front elevational view of a receptacle for paste-perfumery showing my new design;

FIG. 2 is a side elevational view thereof;

FIG. 3 is a top plan view thereof;

FIG. 4 is a bottom plan view thereof;

FIG. 5 is a sectional view thereof taken on the line A—A of FIG. 1;

FIG. 6 is a bottom perspective view thereof;

FIG. 7 is a top perspective view thereof, and;

FIG. 8 is a bottom perspective view in an opened position thereof.

I claim:

The ornamental design for a receptacle for paste-perfumery, substantially as shown.
